UNITED STATES PATENT OFFICE.

HENRY WEHR, OF MORRIS PARK, AND JOSEPH GERMAIN PINEAU, OF WOODHAVEN,
NEW YORK.

AIR-MIXING DEVICE.

Application filed January 14, 1923. Serial No. 529,220.

To all whom it may concern:

Be it known that we, HENRY WEHR and JOSEPH G. PINEAU, citizens of the United States, and residing, respectively, at Morris

5 Park, in the county of Queens and State of New York, and Woodhaven, in the county of Queens and State of New York, have invented certain new and useful Improvements in Air-Mixing Devices, of which the

10 following is a specification.

Our invention relates to air mixing devices for internal combustion engines, and it consists in the combinations, constructions and arrangements herein described and

15 claimed.

An object of our invention is to provide an air mixing device which is adapted to be placed between a carbureter and the inlet of the intake manifold of the engine 20 to which applied and which is provided with means for supplying air to the carburetted mixture passing into the intake manifold to vary the proportions of air and other constituents of the combustible mixture as 25 required to insure the delivery of a satisfactory mixture to the combustion chamber of the engine at all times, irrespective of the speed of the engine.

A further object of the invention is to 30 provide a device of the character described which has means operable by the engine to which the device is applied to control the flow of air through the device in such manner that the volume of indrawn air is 35 decreased as the speed of the engine is increased beyond a determined speed.

A further object of our invention is to 40 provide a device having means for conducting a fluid, such as air, into union with a carburetted mixture passing into the intake manifold of an engine and for diffusing the indrawn fluid through the carburetted mixture to insure the intimate and uniform commingling of the indrawn fluid and the 45 carburetted mixture.

A still further object of the invention is 50 to provide a device which is simple in construction, is adapted for application to engines of various types of automotive vehicles without any change in the construction of such engines being required, and which operates to effect a great saving in the fuel required in the development of a given amount of power.

55 Other objects and advantages will be ap-

parent from the following description and the novel features of the invention will be particularly outlined in the appended claims.

Our invention is illustrated in the accompanying drawings forming a part of this application, in which:

Figure 1 is a view showing a practical embodiment of the invention operatively applied between a carbureter and an intake manifold, portions of the carbureter and manifold being shown,

Figure 2 is a section along the line 2—2 of Figure 1,

Figure 3 is an enlarged perspective view 70 of a fragmentary portion of a plate comprised in the device, showing a valve seat and a valve adapted to cooperate therewith,

Figure 4 is a section through the mechanism shown in Figure 1, the view being taken 75 substantially at right angles to Figure 2,

Figure 5 is a perspective view of the embodiment of the invention shown in the preceding views,

Figure 6 is a perspective view of a modified form of plate embodied in the same invention as that illustrated in the preceding views.

Referring now to the drawings and more particularly to Figures 1 to 5, inclusive, 80 thereof, the numeral 1 denotes a carbureter of a well known type of construction and 2 designates the inlet portion of an intake manifold to which the carbureter 1 is ordinarily attached through the agency of the co-operating flanges 3 and 4, respectively, provided on the carbureter and intake manifold. In carrying out our invention we provide a flat plate 5 conforming in contour with the flanges 3 and 4 and having formed 85 therethrough an opening 6 adapted to register with the outlet of the carbureter 1 and with the inlet of the intake manifold. The plate 5 is secured between the flanges 3 and 4 by bolts 7 or like fastening means.

The plate 5 is formed with bosses 8 and 9 extending from the lower part thereof and formed with bores 10 and 11 enlarged or counterbored at 10' and 11', respectively, the counterbores opening through 103 the walls of the plate 5 into the opening 6, as shown. Ducts 12 and 13 are partly disposed in the counterbores 10' and 11', respectively, and project into the opening to a line substantially coinciding with the di- 110

2
ameter of the opening 6. It is to be noted that the inner diameters of the ducts 12 and 13 are substantially the same as those of the bores 10 and 11 and that the projecting ends of the ducts 12 and 13 are provided with flaring or funnel mouths 14 and 15, respectively.

The bosses 8 and 9 are precisely identical in essential respects and in Fig. 3 the boss 9 is illustrated to advantage. It will be observed that diametrically opposed notches or grooves 16—16 are formed in the outer end thereof. Similar notches are provided for the boss 8 and have been indicated by the same reference numerals. A tubular valve casing 17 is connected to the boss 9 by means of a coupling 18 which threadedly engages both the boss 9 and the tubular valve casing. A valve 19 is slidably disposed within the tubular valve casing 17 and, as illustrated to advantage in Fig. 3, has the general shape of a triangular prism formed with the ends thereof slightly rounded at 20—20. The valve 19 floats between the end of the boss 9 and an annular shoulder 21 formed to extend inwardly from the inner wall of the valve casing 17 at a point somewhat nearer the outer end of the latter than the inner end thereof. The provision of the shoulder 21 reduces the bore of the valve casing, as indicated at 22. The reduced bore 22 is enlarged diametrically and threaded adjacent to its outer end at 23 for engagement with a pet cock 24.

A valve casing 25 is connected with the boss 8 by a coupling 26 and a valve 27 floats between the end of the boss 8 and an internal annular shoulder 28. The valve 27 is precisely identical with the valve 19 and cooperates with the boss 8 and the shoulder 28 in the same manner as the valve 19 co-operates with the boss 9 and the shoulder 21. A reduced bore 29 leads through the shoulder 28 to the outer end of the valve casing 25 and is formed to flare outwardly at its end, as best seen in Fig. 2.

It will be noted that the valve casings 17 and 25 are threaded for practically their entire length and that the couplings 18 and 26 are likewise threaded for practically their entire length to permit of a relatively great longitudinal movement of the valve casings relatively to the bosses to which attached. In order that such movements may be accomplished conveniently, integral enlargements 30—31, respectively, are formed on the valve casings 17 and 25 and are provided with faces, such as indicated at 32 (see Fig. 5) adapted to be engaged by a wrench. Each of the valve casings 17 and 25 is provided with a jamb nut 33 in threaded engagement therewith and adapted to be moved into contact with the end 35 of the coupling to which the valve casing

is attached to releasably lock the valve casing in adjusted position with respect to the boss with which associated.

A street L 34 threadedly engages the valve casing 25, at 35, and is engaged at its outer end by an elbow 36 having one arm thereof arranged in substantially vertical position. A cock 37 is attached to the upright end of the elbow 36 and is provided with an inlet 38 adapted to receive a fill tube 39.

From the foregoing description of the various parts of the device, the operation thereof may be readily understood. The cock 24 has an inlet 40 open to the atmosphere and is initially adjusted and locked in any suitable known manner to permit of a predetermined volume of air passing therethrough along the bore 22. The valve 19 will be moved by gravity to the lower end of the valve casing 17; that is, against the shoulder 21 when the engine to which the device is applied is idle. It is intended that the valve casing 17 shall be adjusted relatively to the end of the boss 9 so as to be positioned at a predetermined distance from the latter, the particular adjustment being determined by the characteristics of the engine with which the device is to be used. Obviously when the engine is started, the suction on the valve casing will draw air through the bore 22 into the valve casing and around the valve therein through the bore 11 and the duct 13. A carburetted mixture is passing from the carburetor 1 through the opening 6 into the inlet of the intake manifold as indicated by the arrows in Figs. 1 and 4 of the drawings, and the air indrawn through the device will be discharged from the projecting duct with a vortex motion in such manner as to be diffused through the mass of carburetted mixture and thereby intimately commingled therewith. As the speed of the engine increases the suction created will be greater and will tend to lift the valve 19 from the shoulder 21 toward the end of the boss 9, thereby first increasing and then decreasing the volume of air indrawn.

When the suction is sufficient to draw the valve against the end of the boss 9, the volume of air permitted to enter the duct 13 will be limited to the capacity of the notches 16—16 since the rounded end of the valve will close the outer end of the bore 11. In idle position the rounded opposite end of the valve will cover the end of the bore 22, although a slight suction will be sufficient to draw air through the bore 22 on account of the conformation of the valve 19. The latter has the corners thereof rounded or squared off slightly and is provided intermediate of its length with a circumferential groove 41. The valve 27 is fashioned similarly and is provided with a circumferential groove 42 intermediate of its length.

The fill tube 39 is designed for use in

priming the engine to which the device is applied. The cock 37 is opened and a desired quantity of a hydrocarbon fuel is poured into the fill pipe and the engine is then started in the usual manner. The cock 37 is then adjusted to permit of a desired volume of air passing therethrough and during the further operation of the engine, air is drawn through the fill tube 39, the cock 37, and the remaining parts which have been described as being arranged between the cock 37 and the boss 8 into the opening 6 for union with the carburetted mixture passing therethrough. If desired, the fill pipe 39 may be removed after the engine has been started.

Obviously a great economy in the use of fuel to develop a given amount of power is effected since a rich mixture will be supplied to the engine when the engine is being started or is operated under a heavy load while a mixture containing a greater percentage of air will be supplied as the speed of the engine is increased. Since the device is under the control of the engine the mixture will be varied as the speed of the engine varies without any action on the part of the operator being required after the initial adjustments have been accomplished. Since the ducts 12 and 13 project into the opening 6 for an appreciable distance and are provided with flaring mouths, the air discharged thereby into the opening 6 will be diffused and thereby intimately commingled with the carburetted mixture so as to provide a uniformly mixed combustible mixture. The ducts 12 and 13 are by preference arranged so that the axes thereof if extended would meet at an angle of approximately 60° with each other and substantially at the upper end of a vertical diameter of the opening.

In Figure 6, we show a plate 50 which is adapted to be placed between the carburetor and intake manifold of engines installed in automotive vehicles of certain types of construction. It will be observed that the plate 50 differs from the plate 5 in that two of the openings 6 are provided and that the duct 12 projects into one of the openings 6 while the duct 13 projects into the other.

The operation of an embodiment of the invention in which the plate 50 is comprised is identical in essential respects with the operation of the embodiment of the invention illustrated in Figs. 1 to 5 inclusive and hereinafter described. In consequence, a

statement of the operation of the modified form is believed to be unnecessary herein.

Obviously, other modifications and adaptations of the forms of the device illustrated in the accompanying drawings may be provided without departing from the spirit and scope of our invention and we, therefore, consider as our own all such modifications and adaptations of the forms of the device illustrated and described as do not depart from the spirit and scope of our invention as outlined in the appended claims.

We claim:

1. In a device of the character described, a tubular fluid intake element adapted to be supported with one end thereof in open communication with a source of suction and having diametrically opposite notches in the wall of the second end thereof, said notches extending from the bore of the tubular intake element to the outer wall thereof, a tubular valve casing having an inlet at one end and being provided with an internal annular shoulder adjacent to the inlet and facing in the direction opposite to the inlet, means connecting the tubular fluid intake element to the valve casing so that the second end of the former is disposed within the latter in spaced confronting relation to the shoulder, and a valve slidably disposed in said valve casing and being adapted to be moved by gravity against said shoulder and by suction against the confronting end of said fluid intake element, said valve having the general shape of a triangular prism having the ends thereof rounded and having a circumferential groove in its wall intermediate of its ends.

2. An air mixing device comprising a plate adapted to be disposed between a carburetor outlet and an intake manifold and having an opening adapted to register substantially with the carburetor outlet, said plate also having two bores opening through the wall of the first named opening, and a pair of air conducting ducts each extending through one of said bores to terminate at their discharge ends beyond the wall of the opening and in the plane of the plate, the discharge ends of the ducts being set at an angle to each other so that the axes thereof intersect at a point beyond the extremities of said discharge end portions and the latter being flared outwardly at their extremities.

HENRY WEHR.
JOSEPH GERMAIN PINEAU.
